UNITED STATES PATENT OFFICE.

WILLIAM B. MELOT, OF FLEETWOOD, PENNSYLVANIA.

GAME-BALL.

SPECIFICATION forming part of Letters Patent No. 289,297, dated November 27, 1883.

Application filed October 24, 1883. (Model.)

To all whom it may concern:

Be it known that I, WILLIAM B. MELOT, a citizen of the United States, residing at Fleetwood, in the county of Berks and State 5 of Pennsylvania, have invented certain new and useful Improvements in Game-Balls, of which the following is a description.

My invention relates to game-balls, and more particularly to base-balls and others 10 which are subjected to rough usage, and which are rapidly worn out.

My invention consists in a ball having a cover, which is secured upon the same by stitching which is entirely upon the inside of 15 the same, and is not exposed or apparent upon the exterior at all. It also consists in the method of fastening the cover on the ball, as will be hereinafter fully described.

Figure 1 is a view of my improved ball. 20 Fig. 2 is the same view of the ball as ordinarily covered. Fig. 3 is a view of one of the two corresponding sections forming the cover. Fig. 4 is a view of the cover half sewed together, and before the ball is inserted. 25 Fig. 5 is a sectional view through the line $y-y$ of Fig. 2, showing the disposition of the stitch in the old form of cover; and Fig. 6 is a section through line $x-x$ of Fig. 1, showing the disposition of the stitch in the new cover.

30 In the drawings, A represents a ball whose cover is composed of two exactly-corresponding pieces, one of which is shown at B. These pieces are fitted together, with the end or wide part of one abutting against the middle 35 or narrow part of the other, so as to make a single continuous seam for the spherical cover, which is formed of two parts only. This pattern for a ball-cover has heretofore been employed, and I only show it as the most 40 convenient and simplest for illustrating my invention.

Now, the usual method of fastening the cover on the ball is by stitches which are passed through the outside edges of the two adjacent 45 parts of the cover, as shown at a in Figs. 2 and 5. These stitches are of course necessarily exposed to abrasion and wear, and soon give way. They are also rough to the hand, and, furthermore, they pass through the 50 outside or hard skin or grain of the leather, which, when it cracks at the stitches, allows the latter to pull out.

In my invention (see Figs. 1, 4, and 6) the line of stitching b is entirely upon the inside, and is not visible upon the outside at all, the adjacent edges of the pattern coming together flush and tight, and leaving but a single line to indicate the blind seam. This prevents the stitching from being worn out by abrasion and rough usage, makes the ball 55 smooth and pleasant to the hand, and, besides, the stitches being set in the tough flesh side of the leather, the leather does not crack and allow the stitches to pull out.

In explaining my method of covering the 60 ball in accordance with my invention, the two patterns or pieces are fitted together around the ball and the stitches laid off and marked on their adjacent edges, both upon the inside and outside. The two pieces are 65 then sewed together from inside until the pieces are about half-way fastened together, or more, as in Fig. 4. The ball is then inserted and the stitching is continued from the outside with a curved needle, care being taken 70 not to draw the stitches until all the stitches are taken. The stitches are then gone over and successively drawn up tight with a hook or awl and the ends of the thread tied and buried in the joint beneath the surface. The 75 seam may be afterward filled with glue or cement, to prevent shrinkage or opening of the same.

In making use of my invention I may employ any desired pattern of cover or form of 80 stitch.

Having thus described my invention, what I claim as new is—

1. A ball having its cover secured by a line of stitching below the exterior surface, as and 85 for the purpose described.

2. The method of covering a ball, which consists in sewing the cover partly together from the inside by stitches that do not penetrate to the exterior, then inserting the ball and continuing the same method of stitching without drawing the sides together, and, finally, drawing the line of stitching to make a closed blind seam, substantially as shown and described. 90

WILLIAM B. MELOT.
